UNITED STATES PATENT OFFICE.

DAVID B. MOISSELLE, OF PHILADELPHIA, PENNSYLVANIA.

RAIL JOINT.

Application filed November 4, 1926. Serial No. 146,119.

My invention relates to welded rail joints.

For some decades, engineers have sought to overcome the disadvantages and shortcomings of the old bolted fish-plate joint.

5 These old joints are not without merit, in that they allow the rails to expand and contract; but they cannot be maintained tight. The result is that the rails pound the head at the receiving end; and the flanges of the 10 wheels cause the rail web to crack through the bolt holes and ultimately break, thereby causing serious trouble. Such joints must be carefully and constantly inspected; and frequent renewals, both of joints and of rails, 15 are required.

Other joints, including welded, poured and cast joints, have been devised which do not loosen easily and have qualities of strength and rigidity; but the advantages that they

20 secure are obtained at the sacrifice of other equally necessary or desirable qualities and involve the creation of new causes of trouble; and, moreover, they do not eliminate certain undesirable features of the bolted joint.

25 Spread rails, cupping of the rails at the joint, and cracking of the web near the head (and indeed actual breakage of the rail if the joints are too heavy for the rails) are among the outstanding weaknesses of so-called improved joints.

The principal conditions that operate to produce these well known objectionable and dangerous conditions are sun, heat and frost, with resultant expansion and contraction 35 that should be fully provided for; side pounding of the wheel flange against the rail head; solidity of the road bed; and in the case of urban street railways, other vehicular traffic.

40 The object of my invention is to provide a rail joint that will secure all the advantages of the old joints and that will provide conditions that are necessary to overcome all their major defects.

45 One preferred embodiment of the invention is shown in the accompanying drawings, in which—

Fig. 1 is a plan view, partly in horizontal section, of my improved rail joint applied to 50 the proximate ends of two aligning rails.

Fig. 2 is a side view of the same.

Fig. 3 is a cross-section on the line 3—3 of Fig. 2.

For the purpose of illustrating an application of the invention, proximate ends of two

side-bearing girder rails *a* are shown. It will be understood, however, that the invention is not limited in its application to a rail of any particular cross-section, it being applicable to rails of the T type, as well as 60 rails of other contours.

Extending longitudinally of, and overlapping, the rails on each side thereof, and welded thereto, are a plurality of bars or rods *b*, *c*, *d* and *e*, which may be of any desired cross-section but which are preferably more or less nearly circular in cross-section. 65

The bars, between their ends, and preferably midway between their ends, are provided with loop, yoke or offset sections *f*, 70 preferably formed by U-shaped bends in, and integral with, the bars.

The bars may or may not be connected at their ends by integral cross connections; but it is preferred to so connect them, preferably by means of integral end cross bars *g*. These connections afford no great advantage in the operation of the joint; but the application of the joint to the rail is thereby facilitated, and (what is of more importance) the proper positioning of each bar relative to the rails and to the other bars is thereby insured. 75

While the number of bars is permissibly variable, I prefer to apply four bars on each side, one of them, *d*, extending along the web midway, or nearly midway between the head and foot of each rail; another, *e*, along the web a short distance below the head; another, *c*, along the crotch between the foot 80 and web; and another *b*, along the rail foot or base not far distant from its edge. The bars are welded to the rail, as indicated by the welds *h*. 85

It is perhaps not essential, but it is of great importance, in order to secure the full advantages of my invention, to so apply the bars that the offsets of the several bars on each side shall extend at different angles to each other and to the rail. Thus, the two 90 upper offsets should preferably extend at about right angles to the web, while the two lower offsets should extend obliquely to the web and to the other two loops. 95

The main highly important characteristics 100 of the new joint are strength and flexibility. These factors are secured without sacrifice of any other desirable factor. On the other hand, other advantages are secured which have never heretofore been obtained. 105

The provision of a plurality of straight bars in place of the solid or poured joint secures strength without weakening the rail, but such straight bars would not provide other factors essential to a joint that is adapted to meet other important requirements. By providing a series of spaced apart bars having mediate loops or other equivalent offsets spanning the gap between the rails, these other factors are completely provided for. The bends, materially aided by the directions in which the bends respectively extend, contribute to making the joint rigid under conditions where rigidity is desirable, since the bends on one side of the rails work against those on the other side. When, however, the rails expand or contract with temperature changes, the bends open or close to permit such expansion; the bends, in fact, functioning as semi-rigid springs. The principal advantages of the invention may be enumerated as follows:

Strength that insures rigidity under all conditions where rigidity is desired, without weakening the rail joint.

Ample provision for expansion and contraction without sacrifice of strength.

Prevention of spread rails due to lack of capacity to freely expand and contract in a straight longitudinal direction.

Elimination of pounding on the head of the rail, due to the fact that the joint cannot loosen.

Elimination of cracking under the head of the rail caused by the side pounding of the head of the rail, the bends acting as springs to which are transmitted, and which absorb, the force of the blows.

Avoidance of subsequent weakening of the rail in that the joint guards against cracking along the line of the junction of head and web and avoids conditions that tend to produce crystallization of the metal.

Durability, in that the joint is capable of outlasting the life of the rails.

Saving in expense of supervision and replacement.

It is important, in welding the bars to the rails, to first weld the bars that engage the bases of the rails so that, before the other bars are applied to the web, the latter, as well as the head of the rail, will have been already conductively heated. It is desirable to weld the bars in the order *b*, *c*, *d* and *e*.

It will be understood that the term "bars" in the claims is used in a broad sense and is not intended to exclude longitudinally extending members of any contour which may be formed by casting integrally a complete structure adapted for application to one side of the rails.

Having now fully described my invention, what I claim and desire to protect by Letters Patent is:

1. In a rail joint, the combination with

the rails, of a plurality of spaced apart bars extending longitudinally of and welded to the rails and provided between their ends with flexible sections, said joint engaging both the web and base portions of the rail. 70

2. In a rail joint, the combination with the rails, of a plurality of spaced apart bars extending longitudinally of and welded to the rails along opposite sides of the rail web and along the rail base on opposite sides of the 75 web and having between their ends laterally extending flexible offset sections.

3. In a rail joint, the combination with the rails, of a plurality of spaced apart bars extending longitudinally of and secured to 80 the rails and overlapping the joint and welded to the rails along the side of the rail web and the upper face of the rail foot, the bars having between their ends laterally offset flexible sections a plurality of which extend at respectively different angles. 85

4. In a rail joint, the combination with the rails, of a plurality of spaced apart bars extending longitudinally of and welded to 90 the rails and overlapping the joint, the bars having between their ends laterally offset flexible sections, and means uniting the bars in an integral structure. 95

5. In a rail joint, the combination with the rails, of four bars extending longitudinally of the rails and spaced apart and overlapping the joint, each bar having a U-bend spanning the joint, two of the bars extending along and welded to the web, a third extending along and secured to the rail at approximately the crotch formed at the junction of web and foot, and the fourth extending along and secured to the foot relatively close to its outer edge. 100

6. In a rail joint, the combination with the rails, of a plurality of spaced apart bars extending longitudinally of and welded to the rails and overlapping the joint and having between their ends offsets a plurality of which extend in different convergent directions, said offsets spanning the space between the ends of the rails. 110

7. In a rail joint, the combination with the rails, of a plurality of spaced apart bars extending longitudinally of and welded to the rails and overlapping the joint and having offsets which span the space between the ends of the rails and one or more of which extend laterally in a substantially horizontal direction while one or more of which extend obliquely upward. 115

8. In a rail joint, the combination with the rails, of a plurality of spaced apart bars extending longitudinally of and secured to the rails and overlapping the joint and welded respectively to the webs and feet of the rails, the bars having U-bends overlapping the joints, the U-bends of one or more of the upper bars and the U-bends of one or more of the lower bars extending 125 130

away from the rails in different and convergent directions.

9. In a rail joint, the combination with the rails, of four bars extending longitudinally of and welded to the rails and spaced apart and overlapping the joint, each bar having a U-bend spanning the joint, two of the bars extending along and secured to the web, a third extending along and secured to the rail at approximately the crotch formed at the junction of web and foot, and the fourth extending along and secured to the foot relatively close to its outer edge, the U-bends of the first two bars extending at approximately right angles to the web and the U-bends of the other two bars extending obliquely upward.

10. A rail joint comprising a plurality of spaced apart bars and provided between their ends with flexible lateral offsets and means connecting the corresponding ends of the bars and providing an integral structure.

11. A rail joint which in end elevation has on opposite sides of the hereinafter specified bends an L-shaped contour and which comprises substantially parallel bars spaced apart, one of the bars being at the angle of the L, one of them relatively near the end of the lower arm of the L and the others along the longer arm of the L, all of the bars having U-bends between their ends, the bends of the first two bars extending obliquely to both arms of the L and the bends of the other bars extending

obliquely relative to the bends of the first two bars.

12. In a rail joint, the combination with the rails, of a plurality of bars extending longitudinally of and welded to the rails and having sections overlapping the joint and adapted to flex to allow expansion of the rails, said bars being substantially round in cross-section and spaced apart.

13. A rail joint comprising a plurality of bars whose opposite end portions extend substantially parallel one to another and provided midway between their end portions with lateral flexible offsets, said bars being so relatively positioned and so spaced apart as to adapt them to be applied to adjoining rails so as to extend longitudinally thereof with the flexible offsets spanning the joint and to be welded to both the rail web and the rail base.

14. A rail joint comprising a plurality of bars extending in the same general direction and spaced apart and provided between their ends with laterally offset flexible sections, and means uniting the bars in an integral structure, the bars being so relatively positioned as to adapt the joint to be applied to adjacent rails, span the joint between them and be welded thereto.

In testimony of which invention, I have hereunto set my hand, at Philadelphia, Pennsylvania, on this 3rd day of November, 1926.

DAVID B. MOISSELLE.
